US0D1106228S

(12) **United States Design Patent** (10) Patent No.: **US D1,106,228 S**
 (45) Date of Patent: ** Dec. 16, 2025

(54) **DISPLAY SCREEN OR PORTION THEREOF WITH A GRAPHICAL USER INTERFACE**

(71) Applicant: **STENO AGENCY, INC.**, Los Angeles, CA (US)

(72) Inventor: **Marie January Cavan Boulas**, Irvine, CA (US)

(73) Assignee: **STENO AGENCY, INC.**, Los Angeles, CA (US)

(**) Term: **15 Years**

(21) Appl. No.: **29/903,784**

(22) Filed: **Sep. 27, 2023**

(51) LOC (15) Cl. **14-04**

(52) U.S. Cl. ....

USPC **D14/485**

(57) **CLAIM**

The ornamental design for a display screen or portion thereof with a graphical user interface as shown and described.

DESCRIPTION

The sole FIGURE is a front view of a display screen or portion thereof with graphical user interface showing our new design to share exhibits in a video conferencing environment.

The outermost broken lines in the FIGURE illustrate a display screen or portion thereof and form no part of the claimed design. The remaining broken lines illustrate portions of the graphical user interface that form no part of the claimed design.

1 Claim, 1 Drawing Sheet
